United States Patent Office

Des. 193,816
Patented Oct. 9, 1962

193,816

CALCULATING MACHINE

Chester J. Abend, Camillus, and Karl E. Kober, Syracuse, N.Y., assignors to Smith-Corona Marchant Inc., New York, N.Y., a corporation of New York

Filed Apr. 23, 1962, Ser. No. 69,817

Term of patent 14 years

(Cl. D64—11)

FIGURE 1 is a front perspective view of a calculating machine showing our new design;

FIGURE 2 is a front elevational view thereof;

FIGURE 3 is a right side elevational view thereof;

FIGURE 4 is a rear perspective view thereof.

The dominant features of our design are shown in full lines.

We claim:

The ornamental design for calculating machine, substantially as shown and described.
